United States Patent

Des. 239,424

Patented Apr. 6, 1976

239,424

SEAT

Giovanni Offredi, Milan, Italy, assignor to Fratelli
Saporiti, Besnate, Varese, Italy

Filed Mar. 18, 1974, Ser. No. 452,411

Term of patent 14 years

Int. Cl. D6—01

U.S. Cl. D6—63

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 1 is a perspective view of an upholstered seat in the form of a love seat embodying the present design;

FIG. 2 is another perspective view of the love seat of FIG. 1;

FIG. 3 is a perspective view looking from the rear of the love seat;

FIG. 4 is a top plan view of said love seat;

FIG. 5 is a side elevational view looking from the right of FIG. 1;

FIG. 6 is a bottom view of said love seat;

FIG. 7 is a perspective view of an upholstered seat in the form of a sofa embodying the present design;

FIG. 8 is a side view looking from the left of FIG. 7;

FIG. 9 is a top plan view of the sofa of FIG. 7;

FIG. 10 is a side view looking from the right of FIG. 7;

FIG. 11 is a bottom view of the FIG. 7 sofa;

FIG. 12 is a rear view of the FIG. 7 sofa; and

FIG. 13 is a perspective view of an upholstered seat in the form of a pair of complementary sectional sofas embodying the present design.

I claim:

The ornamental design for a seat, as shown.
